UNITED STATES PATENT OFFICE.

WALTER S. LANDIS, OF NEW YORK, N. Y., ASSIGNOR TO FRANK S. WASHBURN, OF NEW YORK, N. Y.

METHOD OF PRODUCING NITRIC ACID.

1,292,814.

Specification of Letters Patent.

Patented Jan. 28, 1919.

No Drawing.

Application filed February 24, 1917. Serial No. 150,813.

To all whom it may concern:

Be it known that I, WALTER S. LANDIS, a citizen of the United States, residing at New York city, in the county of New York and State of New York, have invented certain new and useful Improvements in Methods of Producing Nitric Acid; and I do hereby declare the following to be a full, clear, and exact description of the invention, such as will enable others skilled in the art to which it appertains to make and use the same.

This invention relates to a process of producing nitrose gases suitable for making nitric acid, and has for its object to form said gases in a manner more efficient and less costly than has been heretofore proposed.

With this and other objects in view the invention consists in the novel steps and combinations of steps constituting the process, all as will be more fully hereinafter disclosed and particularly pointed out in the claims.

In my Patents No. 1193797, dated Aug. 8, 1916, entitled Process of and apparatus for oxidizing ammonia, and No. 1193796, dated Aug. 8, 1916, and entitled Method of oxidizing ammonia, I have disclosed the essential principles governing the successful oxidation of ammonia to nitrose gases sufficiently high in oxygen to be suitable for the commercial production of nitric acid. These principles may be briefly summarized as follows:—Ammonia not being combustible in air like illuminating gases, its ignition after starting will not propagate itself. In other words, although temperatures of say 600° C. to 700° C. are desired in the catalyst, the direct combustion of ammonia with those proportions of air suitable for the production of nitric acid does not yield temperatures as high as say 500° C.

In oxygen of course it burns without difficulty according to the reaction:

But the products yielded by this reaction have no commercial value commensurate with the cost of the ammonia. Some seventy years ago, it was also noted that ammonia would burn in the presence of a suitable catalyst, according to the equation:

If one desires to write a similar equation

representing the combustion in air, we can assume that the air consists approximately of (4/5N₂ + 1/5O₂) so that our equation would read—

This yields the valuable nitric oxide which can be converted by well known methods into nitrous or nitric acids, or corresponding salts of the same. But as a matter of fact this catalytic combustion with air, or with oxygen, requires more than the theoretical quantity of oxygen to insure complete combustion to those higher oxids of nitrogen suitable for the production of nitric acid, and it is found necessary to use from 1½ to 2½ times the theoretical quantity of air, the excess passing through unchanged. Naturally using such an excess of air as above indicated, the flame temperature will be very much lower than that necessary for maintaining combustion. In order, therefore, to assure a continuous combustion of the ammonia it is necessary that some means of supplying heat to the reaction be employed, otherwise the flame will go out, even if started. Many inventors in this field have supplied this additional heat in their commercial forms of apparatus by preheating the mixture of air and ammonia through a regenerative arrangement of apparatus, whereby a portion of the heat in the products of combustion is transferred to the reagents. This portion of heat must be sufficient to make up that deficiency which the reaction does not supply, so as to insure a flame temperature of some 600° C. to 700° C. necessary for a continuous propagation of the same.

It is likewise well known that ammonia gas is decomposed into nitrogen and hydrogen by heating to comparatively low temperatures; and, therefore, any considerable preheating of the ammonia-air mixture will cause a decomposition of the ammonia before it strikes the catalyst, and so cause a low efficiency of transformation to nitrose gases. It is true that under certain conditions this preheating may not be sufficient to raise the temperature of the ammonia to a point where a serious decomposition will result, but when one considers that the temperatures of the catalysts in use are quite close to the flame temperature, and, therefore, can radiate a large quantity of heat

back into the oncoming gas current, we can readily see that the intentional preheating plus the absorbed radiated heat creates temperatures in the ammonia-air mixture which 5 can cause a considerable decomposition of the ammonia.

In order to more certainly avoid this decomposition of the ammonia, I may in some cases subject the mixture to a cooling action 10 as by passing it through coolers as disclosed in my patents above mentioned.

It is further readily seen that under certain conditions this disassociation may take place to only a small extent, thereby setting 15 free hydrogen which has a very low ignition temperature, and that this hydrogen may then be ignited in the air-mixture, creating an excessive local temperature as it burns, and so further increasing this decomposition 20 of ammonia before striking the catalyzer. As a matter of fact, it has been found that most commercial types of apparatus operating upon this principle decompose from 5 to 15% of the ammonia by a combination of 25 the above causes before the ammonia-air mixture ever strikes the catalyzer, and therefore, they yield a correspondingly low efficiency of transformation of ammonia into nitrose gases.

30 In the process of my said Patent No. 1193796, I am careful, as above stated, to employ an excess of air above that theoretically required, in order to attain the desired higher oxids of nitrogen, and owing to this 35 said excess of air, the catalyzer must be continuously supplied with heat from an outside source.

In this invention, on the other hand, I avoid the necessity of artificially heating the 40 catalyzers, by enriching the air to be mixed with the ammonia with a quantity of oxygen to make the reaction self propagating. That is to say, I have found that if instead of using atmospheric air containing, 45 say 20% oxygen and 80% nitrogen, one employs an excess of an enriched air containing say 30% to 40% oxygen the catalytic oxidizing reaction becomes self supporting, even though said excess of air is present; and the 50 catalyzers need not in such cases be artificially heated except incidentally, or to start the reaction.

I have further found that a convenient method of obtaining this enriched air, is by 55 liquefying atmospheric air, and permitting the nitrogen to boil off until about 40% oxygen or a somewhat higher percentage is left. The ammonia used in this process can be conveniently obtained by treating calcium cyanamid with steam, and the nitrogen boiled off can be conveniently used in the manufacture of said cyanamid. It therefore follows that the waste gases from a liquid air plant producing nitrogen can be 60 employed to eliminate the necessity of heat-

ing the catalyzers after the reaction starts, it being only necessary to raise them to an initial starting temperature, after which the reaction is so strongly exothermic that it will continue of itself.

70

In the use of ordinary air, the concentration of the nitrose gases coming from the catalyzers is often not above 6% to 10%; but by employing an excess of an enriched gas, such as that disclosed, not only are concentrations of the exit gases of at least double these values easily attained but the oxygen enriched air being in excess considerable free oxygen passes the catalyzers and serves to oxidize the nitrose gases present to 80 those higher oxids of nitrogen so necessary for the commercial production of nitric acid. I therefore produce a greater efficiency than heretofore in condensation and concentration yields; and I also obtain by this procedure higher percentages of nitric acid, while effecting a very great reduction in the cost of the absorption apparatus receiving said gases.

85

It, of course, is convenient in this process 90 to employ a cooler through which the mixture passes before reaching the catalyzers and also to employ an electric circuit to raise the catalyzer to the ignition temperature all as disclosed in my said patents 95 above, but these are not necessary in all cases. For I find after the lower oxids of nitrogen are formed in or about the catalyzer mass the free oxygen that has been provided beyond the catalyzer by the above 100 mentioned excess of enriched air serves to further oxidize the nitrogen to the higher oxids which are readily converted into nitric acid upon contact with water.

100

This invention should be carefully distinguished from those prior processes which produce free nitrogen or do not produce these said higher oxids of nitrogen as their main product, for such processes cannot commercially produce nitric acid as above 110 pointed out.

It is obvious that those skilled in the art may vary the details of the invention without departing from the spirit thereof, and therefore, I do not wish to be limited to the 115 above disclosure except as may be required by the claims.

What I claim is:—

1. The process of producing the higher oxids of nitrogen suitable for making nitric 120 acid which consists in providing a mixture of oxygen, air and ammonia containing an excess of air and sufficient oxygen to sustain the reaction, and subjecting said mixture to the action of a hot catalyzer, substantially 125 as described.

2. The process of oxidizing ammonia to form higher oxids of nitrogen suitable for making nitric acid which consists in providing a mixture of oxygen, ammonia and air 130

in excess containing above 25% oxygen; passing said mixture through a catalyzer; and raising said catalyzer to a temperature sufficient to start the reaction, substantially as described.

3. The process of oxidizing ammonia to form higher oxids of nitrogen which consists in providing a mixture of ammonia, oxygen and air in excess, said mixture containing above 25% of oxygen; subjecting said mixture to a cooling action; subjecting the cooled mixture to the action of a catalyzer; and raising said catalyzer to a temperature sufficient to start the reaction, substantially as described.

4. The process of producing higher oxids

of nitrogen suitable for making nitric acid which consists in providing a mixture of oxygen, air and ammonia containing an excess of air and sufficient oxygen to sustain the reaction, but an insufficient quantity of nitrogen to lower the flame temperature below the ignition point, and subjecting said mixture to the action of a hot catalyzer, substantially as described.

25
In testimony whereof I affix my signature, in presence of two witnesses.

WALTER S. LANDIS.
